UNITED STATES PATENT OFFICE.

FREDERICK A. ANTONCICH, OF BROOKLYN, NEW YORK.

BOAT-LAUNCHING DEVICE.

Application filed March 23, 1923, Serial No. 627,163. Renewed September 25, 1926.

My invention relates to a life boat launching device for vessels, docks, life-saving stations, etc., and is addressed to provide means for launching life boats to prevent the danger of the boats upsetting during the operation, to facilitate the launching, and making the operation generally safe and more mechanical than heretofore.

In the drawings, in which like numerals refer to like parts.

Fig. 1 is a vertical cross section of a portion of a boat showing three decks, the upper two of which are provided with life boats and means for launching same.

Fig. 2 is a detail view on an enlarged scale showing means for operating the life boat davits.

Fig. 3 is a top diagrammatic view showing the location of the boats, looking down from the top of Fig. 1 in the direction of the arrow.

Fig. 4 is a fragmentary view showing the position of the life boats during the course of operation.

Fig. 5 is a detail view showing the method of releasing the life boat from the davits.

Figs. 6, 7 and 8 are details of the clutch and operating parts for connecting the davit raising means with a source of power.

Figs. 9 and 10 are details of the guide beam connections with davit posts.

Figs. 11, 12 and 13 are details of bridge and connections.

Figs. 14 and 15 are details of davit turning mechanism.

In the drawings, numerals 1, 2, 3 and 4 represent life boats, life boats 1 and 2 being on the upper deck and life boats 3 and 4 being on the lower deck. Normally life boats 1 and 3 would be inside and resting in place on the decks in the cradle ready upon notice to be moved to the position shown in Fig. 1 by the operating mechanism hereinafter described. For convenience, I have shown life boats 1 and 3 beyond the rail of the boat ready to receive their passengers before lowering. If desired, the loading of the life boats with passengers could take place either while the boat was in the cradle or on the deck, and before it was moved to the position shown by life boats 1 and 3. The davits

5 supporting the life boat are arranged in pairs, as shown in Fig. 1, so that when one life boat has been moved to the position shown by life boat 1, life boat 2 on the deck 55 can be connected with the davit ready for removal to the side of the boat in position to be lowered. The davits 5—5 are fixedly connected to a vertical column 6. This vertical column 6 is mounted in suitable 60 journals 7 and rests on ball bearings 8. These ball bearings in turn rest upon screw-threaded spindles 9, mounted in journal brackets 10 and have a threaded spiral pinion 11 which meshes with spiral gear 12 65 fixedly mounted on shaft 13. This shaft is held in suitable bearings 14. One end of this shaft is fixedly attached by a suitable key to the beveled gear 15. This beveled gear is in mesh with a beveled gear 16 loosely 70 mounted on a stud 17 held by the bracket 18. This beveled gear 16 is held in mesh with beveled gear 19 which is loosely mounted on shaft 20. This shaft is provided with a sleeve 22 adapted to slide on the shaft 20, 75 being splined thereto so as to rotate therewith. The exterior central portion of this sleeve is circular while the end exterior portions are hexagonal, as shown in Figs. 6 and 7. Surrounding this sleeve is a shell 22^a so which is attached by rivets or screws, as shown in Fig. 6, to the central portion of the sleeve. Between the shell 22^a and the hexagonal portion of the sleeve there are spaces at each end of the sleeve in which are mounted springs 27 which press at their inner sides against the central portion of sleeve 22 and at their outer ends against movable claw members 23 and 24 so as to permit motion of the claw members parallel to the shaft. The 80 shell 22^a is turned inward at its ends, as shown, so as to retain the claw members in normal position. These claw members are adapted to mesh claws 23 with pockets or notches 25 on beveled gear 15 and claws 24 with pockets or notches 26 on beveled gear 19. These claws 23 and 24 are held in their normal position by springs 27 and are adapted, so that when the sleeve is moved toward or away from the beveled gears 15 85 and 19, to engage with the pockets or notches 90 on beveled gears 15 or 19, depending upon 95 100

the direction in which the sleeve 22 is moved. As sleeve 22 rotates with the shaft 20 if it is moved in the direction of beveled gear 15, claws 23 engage with pockets or notches 25 and cause beveled gear 15 to rotate in the same direction as shaft 20 is rotating. This in turn causes shaft 13 to rotate in the same direction, thereby rotating spiral 12, meshing with spiral 11 and raising column 6 through 10 spindle 9, and ball bearings 8 to the desired position.

When it is desired to lower column 9 operation of the sleeve 22 is reversed, that is, the sleeve is moved toward beveled gear 19, 15 claws 24 engaging with pockets or notches 26, causing beveled gear 19 to become locked to shaft 20 and rotate therewith. Beveled gear 19 then rotates beveled gear 15 through the medium of idler beveled gear 16 in the 20 opposite direction to shaft 20 and causes column 6 through chain of gears 12, 11, ball bearings 8 and gravity to lower to the desired position. The operation of this clutch is controlled by hand lever 28, pivoted at 25 29 to bracket 18. Shaft 20 is provided with beveled gear 30 fixedly secured to it by suitable key which meshes with beveled pinion 31 pinned to a vertical shaft 32. Vertical shaft 32 is mounted in suitable bearings 33 30 and 34. At the lower end of vertical shaft 32 is pinned or keyed a worm wheel 35. 36 is an electric motor having a shaft 37 on which is fixedly mounted a worm 38 which meshes with the worm wheel 35 35 mounted on the lower end of vertical shaft 32. This motor is connected with any suitable source of electric power and while I have shown an electric motor any other suitable means may be provided.

With the life boat 1 on the deck and the clutch thrown in so as to raise the column 6, as described above, column 6 gradually rises. As it does so, columns 6—6 gradually turn in opposite directions by reason 45 of a roller 39 mounted on pin 40 secured to a bracket 41. This roller is rotated in a spiral groove 42 in the sleeve 43 which sleeve is loosely mounted on column 6 and held in fixed vertical position with relation 50 to column 6 by the collars 45 and 46. Column 6 has keyed to it a notched member 44. As column 6 rises, collar 45 carries up with the column sleeve 43 and roller 39 in the groove 42 and causes the sleeve 43 to rotate. As sleeve 43 rotates spring pressed 55 pawl 47 mounted on the sleeve 43 engages with the notch 48 on the member 44 keyed to the column 6 and causes column 6 to rotate. As shown, columns 6—6 carrying 60 davits for the opposite ends of the boats operate in opposite directions so that, as hereafter described, the boat is lowered between them, as shown in Fig. 4, to its launching position.

Life boats are attached to the davits by

tackle 49 which consists, as shown in Fig. 5, of cable or rope 50 and pulleys 51, the pulleys being attached, as shown in Fig. 5, to the outer ends of the davits 5. The lower end of the tackle 49 is attached to a guide beam 52 by suitable bolts. Below the beam there is a yoke 53, the lower end of which is detachably connected by the bolt 54 to life boat. This yoke 53 in the forward end of the life boat is provided with a sheave pulley 55. The yoke 53 at the rear end of the boat is likewise detachably connected to the bottom end of the boat and is also provided with a brake drum and windlass 56 controlled by the cam lever 57 pivoted to the 80 yoke 53 by pivots 58. A suitable brake band is attached to the lever 57 at opposite ends of a bell crank lever 59 and 60. The hand lever 57 and bell crank levers 59 and 60 are integral.

The brake 61 consists of a suitable band, belt or other flexible member which surrounds the brake drum 56 and by operating the hand lever 57 so as to move the bell crank levers more or less tension is brought to bear on the drum through the brake flexible member 61 to control the rotation of the drum and regulate the speed of lowering of the boat through the tackle 49. When the life boat has been launched in the water and it is desired to release it from the boat the hand wheel 62 is rotated. This hand wheel 62 is fixedly attached to a sleeve 63 within which at one end is a right thread engaging a similar thread on one end of one of the bolts 54 and in the other end of the sleeve is a left thread engaging a similar thread on the adjacent end of the other bolt 54 so that as sleeve 63 is rotated by wheel 62 it draws the bolts 54, 54 toward each other and releases them from engagement with the lower ends of the yokes 53, 53 thereby disengaging the boat which is now free to move away from the vessel. As the life boat moves away from the vessel the weight of the 105 tackle, the brake drum, etc., will cause the tackle to run out from engagement with the pulley on the davits and thus released from the davits will sink or float away and not encumber further operation of the life boat launching apparatus. To prevent the davits from swinging with the positive means for locking them in the position shown in Fig. 1, or, in other words, to lock them after they have rotated a distance of 180°, I have provided means for locking the column 6 after each movement of 180° as follows. A bracket 108 carries a guide rod 109, as shown in Fig. 2, and slidably mounted upon said guide rod and held in position by the bracket is a spring pressed pawl 110 which engages with a notch 111 in the collar 44 which is keyed to the column 6.

As described above, the life boat is first raised from its cradle. The davits then ro-

tate, carrying the life boat out between them until it is in a position slightly above that shown by life boat 1 in Fig. 1 when the davits will be lowered by the column 6 until 5 the life boat has reached the actual position shown in Fig. 1 when it is ready for launching. This operation of raising the life boat, passing it out and then lowering it to the position shown by life boat 1 in Fig. 1 is 10 as follows.

A clutch heretofore described connecting shafts 13 and 20 is automatically operated as follows. A collar lever 28^a pivoted at 29 is provided at its lower end with a pin 29^a. 15 A lever 65 pivoted at 65^a to shaft 66 is provided with a bifurcated member 80. Rod 66 is provided at its inner end with a pin carrying an anti-friction roller 81 which operates in a groove 68 in the side of worm gear 69. 20 This groove is arranged concentrically of the gear 69 having three positions as clearly shown in Fig. 2 in which the position furthest removed from the center or shaft is the position for raising the column 6. The position nearest to the center or shaft is the position for lowering the column 6 and the position intermediate the two is the neutral position, as shown in Fig. 2, so that the clutch connecting shafts 13 and 20 is neutral 25 30 and shaft 13 is not in rotating engagement with shaft 20. Gear 69 mounted on shaft 70 is in mesh with worm 71 mounted on shaft 72. Fixedly mounted on this shaft 72 is a ratchet 73. In engagement with this ratchet 35 is a spring pressed pawl 74 pivoted on an arm 75 which arm at one end is loosely mounted on the shaft 72 and at the other end pinned to the eccentric strap 77 by pin 76 of eccentric 78 which is mounted on shaft 20 40 so that as the shaft 20 operates the eccentric 78 keyed to and rotating with the eccentric 77 causes a reciprocating motion of the arm upon which is mounted pawl 74 which engages with the ratchet 73 to cause intermittent rotation thereof, which rotation is in turn transmitted to worm wheel 69 through worm 71 mounted on shaft 72. When the life boat has been raised, carried out between the 45 davits and lowered to the position of life boat 1 shown in Fig. 1, it is desirable that the clutch be in neutral position and be held there until the life boat has been launched. To provide for this I have arranged an automatic release to release the pawl 74 from 50 55 engagement with the ratchet 73.

When the life boat is being lowered into the position shown in Fig. 1, the guide beam 52, which in the case of the boats on the upper deck is formed in the shape shown in Fig. 3 or any desired shape so as to extend beyond the ends of the boats on the lower deck, comes in contact with the guide leaders 83 fixedly secured to the side of the vessel. These leaders are preferably I beams 60 65 in cross section, or of similar construction

to provide suitable guide rails or leaders. These guide beams 52 are normally in the position shown to the right in Fig. 1 where they are locked to an arm 84 of sleeve 85. This locking means consists of a spring 70 pressed pawl 85 mounted in housing 86 and provided with a spring 87 to keep the pawl in normal locking position. The guide beam 52 is provided with extensions 88 which extend outwardly and around the head 89 of 75 the arm 84 of sleeve 85. It is in this head that the pawl 87 is located and, as shown in Figs. 9 and 10, the pawl is held in its normal position extending into an opening 90 in the guide beam 52 so as to lock the guide beam 52 to the arm 84. At the end of pawl 85 opposite to the end where it engages with the opening 90 in the guide beam 52 there is provided a T head 93 which rests on opposite sides of the bifurcated latch 91 which 80 is provided with a cam shaped portion 92 so that as the latch is raised the T head 93 of the pawl 85 is withdrawn in opposition to the spring 87 so as to disengage it from the opening 90 and release guide beam 52 from engagement with arm 84. The operation of this releasing latch is caused by the lowering of the davit into the position shown in Fig. 1. In Fig. 10 I have shown the leaders 83 just before the davit has been 85 lowered to permit the guide beam 52 to engage with the leaders 83. As will be seen, the latch 91 has a projecting member 94 that engages with the upper end of the leaders 83 so that as the arm 84 is lowered through 90 the lowering of the davit and the column 6, the member 94 contacting with the upper end of the leader 83 leaves the cam member 92 of latch 91 and withdraws pawl 85 from engagement with the guide beam 52. At the same time the guide beam 52 is lowered and being in position to act with the leader 83 engages therewith and holds the life boat in fixed position with relation to the side of the vessel. As the life boat is then lowered, 100 as heretofore described, the leaders 83 maintain the same relative position between the side of the vessel and the life boat irrespective of the position of the vessel while the connections between the life boat and the guide beam 52 and the davits permit the life boat to always maintain a horizontal or parallel position to the surface of the water. 105

The boats on the lower deck are provided with similar leaders 83 operating in the same way. These leaders, however, are shorter and are on a different vertical plane from the leaders for the life boats on the upper deck. To enable preparation to launch another boat from the same deck, the arm 84 must be rotated on the column 6 so as to bring it in position to engage with guide member 52 on the next life boat to be lowered. To permit this operation the arm 84 is attached to or integral with sleeve 85. 110 115 120 125 130

This sleeve 85 rests upon a collar 95 fixed to the column 6. As column 6 is raised, sleeve 85 slidably mounted on column 6 is caused to rotate with the column by means of the spring pressed dog 96 pivoted on the sleeve 85 which engages with a spline 97 in the column 6. In Fig. 15 this top view is shown and the details of this construction.

On the upper decks, by reason of the fact that the boats must be carried to a position where in lowering they will clear the boats on the decks below, they have to be carried out beyond the side of the boat and in order to get into them I have provided a bridge 98 held in fixed position to the side of the vessel by tie rods 99 and supports 100. This bridge 98 is provided with suitable side rails 101. In the passage of the life boat between the davits into the position shown in Fig. 1 by life boat 1, it is advisable that one of the rails 101 should be lowered so as not to interfere with the life boat and its passage out to the launching position. For this purpose I have provided the side rail so that it is normally held in operative position by means of the torsional spring 102 which keeps the guide rail 101 in its position at right angles to the bridge 98. As the life boat is being passed out to its launching position this rail is lowered by means of mutilated gear 103 splined to column 6 as shown in Figs. 11 and 12. This mutilated gear engages with a beveled pinion 104 fixed to rock shaft 105. This rock shaft has fixedly secured to it arms 106 which are connected with the rail 101 by suitable links 107 so that column 6 rotates and the teeth of the mutilated gear engage with the teeth of pinion 104. Shaft 105 is rotated and arms 106 are moved so as to cause the links 107 to move the rails 101 down from a vertical position to a horizontal position, as shown in Fig. 3, in opposition to torsional spring 102. When the last tooth of the mutilated gear has passed from engagement with the pinion 104 the torsional spring 102 again raises the rail 101 to its normal position.

While I have described the operation of my invention by reference to the launching of the boats on the upper deck, I would have it understood that the same means are used for operating the boats on other decks and the davits and guide beams being merely of different sizes depending upon the number of decks from which boats are to be launched.

Having described my invention, what I claim as new and desire to secure by Letters Patent is:

1. In a boat launching device, a davit, a support for said davit, means for raising and lowering said davit, and means for moving said davit, means for guiding the boat to control its position while being

lowered with relation to the side of a vessel from which it is being lowered and means within the boat being lowered for detaching said guiding means.

2. In a boat launching device, a davit, a support for said davit, means for raising and lowering said davit, means for carrying a boat in engagement with said davit, and means for moving said davit, means for guiding the boat to control its position while being lowered with relation to the side of a vessel from which it is being lowered and means within the boat being lowered for detaching said guiding means.

3. In a boat launching device, a davit, a support for said davit, means for raising and lowering said davit, and means for rotating said davit, means for guiding the boat to control its position while being lowered with relation to the side of a vessel from which it is being lowered and means within the boat being lowered for detaching said guiding means.

4. In a boat launching device, a davit, a support for said davit, means for raising and lowering said davit, means for carrying a boat in engagement with said davit, and means for rotating said davit, means for guiding the boat to control its position while being lowered with relation to the side of a vessel from which it is being lowered and means within the boat being lowered for detaching said guiding means.

5. In a boat launching device, a davit, a support for said davit, means for raising and lowering said davit, and means for rotating said davit 180 degrees, means for guiding the boat to control its position while being lowered with relation to the side of a vessel from which it is being lowered and means within the boat being lowered for detaching said guiding means.

6. In a boat launching device, a davit, a support for said davit, means for raising and lowering said davit, means for carrying a boat in engagement with said davit, and means for rotating said davit 180 degrees, means for guiding the boat to control its position while being lowered with relation to the side of a vessel from which it is being lowered and means within the boat being lowered for detaching said guiding means.

7. In a boat launching device, a pair of davits, means for raising and rotating said davits in opposite directions and lowering said davits, and means for supporting a boat attached to said davits, means for guiding the boat to control its position while being lowered with relation to the side of a vessel from which it is being lowered and means within the boat being lowered for detaching said guiding means.

8. In a boat launching device, a pair of davits, means for rotating said davits in opposite directions, means for supporting a

boat attached to said davits, guideways and means detachably connected to a boat and to said guideways for guiding a boat as it is being launched from said davits and 5 means located within said boat for detaching said guiding means.

9. In a boat launching device, a pair of davits, means for rotating said davits in opposite directions, means for supporting a 10 boat attached to said davits, guideways and means detachably connected to a boat and to said guideways for guiding a boat as it is being launched from said davits so arranged as to control its position with relation to the side of the body from which it 15 is being launched and means located within said boat for detaching said guiding means.

10. In a boat launching device, a pair of davits, means for rotating said davits in opposite directions, means for supporting a 20 boat attached to said davits, and guideways fixed to the body from which the boat is to be launched, means independent of said supporting means detachably connected with 25 a boat and with said guideways for controlling the position of the boat while being launched and means located within said boat for detaching said guiding means.

11. In a boat launching device, a pair of 30 davits, means for rotating said davits in opposite directions, means for supporting a boat attached to said davits, guideways fixed to the body from which the boat is to be launched, and means independent of said 35 supporting means detachably connected with the boat and engaging with said guideways for controlling the position of the boat while being launched, and means located within said boat for detaching said guiding means.

12. In a boat launching device, a pair of 40 davits, means for rotating said davits in opposite directions, means for supporting a boat attached to said davits, guideways fixed to the body from which the boat is to be launched, and means independent of said 45 supporting means connected with the boat and engaging with said guideways for controlling the position of the boat while being launched, and means located within said boat for detaching said guiding means.

13. In a boat launching device, a pair of 50 davits, means for rotating said davits in opposite directions, means for supporting a boat attached to said davits, a bridge leading to a boat attached to said davits, and a folding side rail for said bridge normally held in operative position, said side rail being operated by rotation of the davit.

14. In a boat launching device, a pair of 60 davits, means for rotating said davits in opposite directions, means for supporting a boat attached to said davits, a bridge leading to a boat attached to said davits, a folding side rail for said bridge normally held in operative position, and means, operated

by the means for rotating the davits, for operating said folding rail.

15. In a boat launching device, a davit, a support for said davit, an arm detachably connected to said support and with a boat to be launched, guiding means fixed to the body from which a boat is to be launched, and means for disengaging said arm from the support when said arm is brought into register with said guiding means. 75

16. In a boat launching device, a davit, a rotating support for said davit, an arm detachably connected to said support and with a boat to be launched, guiding means fixed to the body from which a boat is to be 80 launched, and means for disengaging said arm from the support when registering with said guiding means.

17. In a boat launching device, a davit, a vertically moving support for said davit, an 85 arm detachably connected to said support and with a boat to be launched, guiding means fixed to the body from which a boat is to be launched, and means for disengaging said arm from the support when registering with 90 said guiding means.

18. In a boat launching device, a davit, a rotating support for said davit, means for rotating said support, an arm detachably connected to said support and with a boat to be launched, guiding means fixed to the 95 body from which a boat is to be launched, and means for disengaging said arm from the support when registering with said guiding means. 100

19. In a boat launching device, a davit, a vertically moving support for said davit, means for vertically moving said support, an arm detachably connected to said support and with a boat to be launched, guiding means fixed to the body from which a boat is to be launched, and means for disengaging said arm from the support when registering with 105 said guiding means.

20. In a boat launching device, a davit, a rotating and vertically moving support for said davit, means for rotating and means for vertically moving said support, an arm detachably connected to said support and with a boat to be launched, guiding means fixed to the body from which a boat is to be launched, and means for disengaging said arm from the support when registering with 110 said guiding means. 115

21. In a boat launching device, a davit, a rotating support for said davit, means for locking said support against rotation after it has rotated 180 degrees, an arm detachably connected to said support and with a boat to be launched, guiding means fixed to the body from which a boat is to be launched, and means for disengaging said arm from the support when registering with 120 said guiding means. 125

22. In a boat launching device, a davit, a 130

rotating and vertically moving support to said davit, means for rotating and means for vertically moving said support arranged so as to rotate said support during its vertical movement, an arm detachably connected to said support and with a boat to be launched, guiding means fixed to the body from which

a boat is to be launched, and means for disengaging said arm from the support when registering with said guiding means. ¹⁰

In witness whereof, I have signed my name to this specification.

FREDERICK A. ANTONCICH.
